UNITED STATES PATENT OFFICE.

ROBERT H. MULLEN, OF CINCINNATI, OHIO.

DRIVING-LINE.

SPECIFICATION forming part of Letters Patent No. 340,517, dated April 20, 1886.

Application filed February 15, 1886. Serial No. 192,022. (No model.)

To all whom it may concern:

Be it known that I, ROBERT H. MULLEN, of Cincinnati, Hamilton county, Ohio, have invented a new and useful Improvement in Driving-Reins, of which the following is a specification.

My invention is particularly designed as an improvement on those driving or check lines or reins for double harness, which consist of a single line composed of rope or cordage, which at its forward extremity branches into two bridle lines, also of cordage for respective attachment to the bits of the near and off horses or mules.

15 In the accompanying drawings, Figure 1 represents, full size, the forward end of my single line. Fig. 2 shows the same portion of the single line having engaged within its double eyelet the piece of cordage, which, after its ends have been provided with suitable snaps, constitutes the bridle lines of the two horses or mules. Fig. 3 shows the same after attachment of the snaps and the drawing of the cord tightly into the eyelet in such manner as to secure the desired discrepancy in 25 length of the two branches. In this figure the double eyelet is represented by section.

A represents the front part of a piece of cordage which constitutes the driving line or 30 rein proper.

B is a metal double eyelet, which is, by means of its toothed and tubular shank or clip b, permanently attached to the front extremity of the cord A. The said eyelet has two eyes or orifices, of which the eye b', nearest the shank, is circular and of diameter a little larger than that of the cord. The other eye, b'', is oblong, and has its greatest length transverse of the shank.

Rove singly through the eye b' and doubly to and in opposite directions through the eye b'' is a piece of cordage, C, which, after having been thus rove, is tipped with snaps D D', which may be secured to the cord by means of shanks d similar to the shank b. The two 45 branches e e' of the bridle cord C being drawn through and adjusted to the desired relative lengths and hauled tight within the eyelet, as shown in Fig. 3, retain the lengths thus given to them.

Should it be desired to readjust the relative lengths of the branches, such readjustment is easily and quickly effected after first slackening of the cord C within the eyelet, as seen in Fig. 2.

55 For double-line driving it is merely necessary to duplicate the line shown in Fig. 3.

It is manifest that buckles or their equivalents may be substituted for the snap hooks.

The device is intended for farmers' and 60 teamsters' use in place of the much more costly harness made of leather.

I claim as new and of my invention—

The driving-rein or check-line for double harness, comprising a single length of rope or 65 cord having a clip secured thereto, as described, said clip being provided with a round and an oblong eye, one end of the rope or cord passed through the round eye, and both through the oblong one, and having at their 70 free ends suitable fastenings, substantially as set forth.

In testimony of which invention I hereunto set my hand.

ROBERT H. MULLEN.
